WARREN ISAIAH MOULTON, OF BOSTON, MASSACHUSETTS, ASSIGNOR OF ONE-FOURTH
TO ALFRED A. McDAVITT AND ONE-FOURTH TO CORNELIUS E. McLAUGHLIN, BOTH
OF BOSTON, MASSACHUSETTS

AUTOMOBILE WINDOW SCREEN

Application filed August 21, 1931. Serial No. 558,595.

The present invention comprehends the provision of a window screen, and more particularly a novel construction of means for mounting the screen above the slidable windows of a motor-operated vehicle, the screen being normally positioned so as not to interfere with the closing of the window, and capable of being easily and conveniently lowered for use, subsequent to opening of the window.

In carrying out my invention, I employ brackets of novel construction in which the screen roller is journaled, and which brackets assist in guiding the screen, and also limiting the upward movement of the screen as it is wound about its roller.

The nature and advantages of the invention will be better understood when the following detail description is read in connection with the accompanying drawing, the invention residing in the construction, combination and arrangement of parts as claimed.

In the drawing forming part of this application like numerals of reference indicate similar parts in the several views and wherein:

Figure 1 is a vertical sectional view illustrating the construction of the window frame and the mounting of the screen.

Figure 2 is a perspective view of one of the brackets.

Figure 3 is a fragmentary view of the finishing strip of the window structure.

As hereinabove stated, the invention is primarily intended for use in conjunction with closed automobiles, and while the invention is herein illustrated in connection with an automobile door having the usual window frame structure at the upper portion thereof, to accommodate a sliding window pane, I of course desire to have it understood that the invention is intended to be used on the windows as well as the doors of an automobile, and that its general application in this connection is contemplated by the claims.

Referring to the drawing in detail, 10 indicates a portion of a door of the type used on motor operated vehicles, the upper por-

tion of which is constructed to form a window frame to receive a sliding window pane 11, and which pane is guided in its movements by opposed channel-shaped guides 12 lined with felt or other suitable material 13 in the ordinary well known manner. In accordance with the present invention, the upper cross member 14 of the window frame structure is of hollow formation to accommodate the screen, and in which the screen is normally housed in an out-of-the-way position, so that the window pane 11 can be fully closed, and manipulated in the ordinary well known manner without any interference whatsoever on the part or presence of the screen. This hollow upper cross member 14 is arranged upon the finishing strip 15 of the window frame structure, and this finishing strip is cut away along one of its longitudinal edges as at 16 in Figure 3, for a purpose to be hereinafter described.

Arranged within the hollow cross member 14 is a pair of spaced brackets, preferably of the construction illustrated in Figure 2. Each bracket includes a vertically disposed attaching flange 17 having openings 18 to accommodate suitable fastening elements by means of which the bracket is secured within the member 14 as illustrated. Each bracket also includes a right angularly disposed vertical flange 19 formed with a central opening 20, while these flanges are connected by a bottom wall 21 having a slot 22 leading from one edge of the bottom wall in the direction of the flange 19. When the brackets are secured within the hollow cross member 14 of the window frame structure, the flanges 19 are disposed in confronting relation, and journaled in the openings 20 of these flanges of the respective brackets 80 is the spring roller 23. A screen 24 is adapted to be wound about and unwound from the roller 23, and the roller is formed with an instruck portion 25 to form a groove to accommodate one end of the screen, which end is clamped or otherwise suitably secured to the roller within said groove. Carried by the free end of the screen is a channel-shaped bar or member 26 in which is slidably mounted a pair of retaining bars 27, which are nor-

5 mally projected beyond the ends of the channel-shaped member 26 by means of springs, to be received by spaced openings formed in the window pane guides, to hold the screen 24 fixed relatively thereto in any given position. Each retaining bar is provided with a manipulating handle or element 30 arranged centrally at the lower edge of the screen, and which elements are adapted to be moved 10 toward each other to compress the springs, in order to release the screen when it is desired to either raise or lower the screen as will be readily understood. The channel-shaped member 26 reposes upon and is connected with an inverted U-shaped bar 31 which receives a rubber strip 32 having a groove along its lower edge to receive the adjacent edge of the window pane 11 when these parts are engaged or associated as 15 20 shown in Figure 1. As illustrated in Figure 3, the hollow cross member 14 of the window frame structure is also provided with a restricting opening along its bottom and at one side of the finishing strip 15, through 25 30 35 40 45 50 which the screen 24 passes while being wound about or unwound from the roller 23. In the normal position of the screen as shown in Figure 1, the screen is wholly disposed within the hollow cross member 14 and the cut away portion 16 of the finishing strip 15 receives a portion of the manipulating handles as shown in this figure, so that the screen can be elevated to such a point as not to interfere with the closing movements of 55 the window pane 11, and thus allow the window pane to be fully closed to exclude the elements. It is of course to be understood that both the window pane 11 and the screen 24 are independently operable, so that the window pane 11 can be raised or lowered without any interference on the part of the screen, and when use of the screen is desired, the window pane 11 can be lowered any desired distance, after which the screen 45 is lowered to cover the window opening, with the lower edge of the screen associated with the upper edge of the window pane as shown in Figure 1. The screen is held in any given position by means of the retaining rods 27 above described.

55 It will be noted that the opening in the bottom of the hollow cross member 14, as well as the slots 22 of the brackets above described are arranged above and in line with the guides 12 for the window pane 11, so that when the screen 24 is lowered, it is initially guided in its movements through the slots 22 of the brackets, and then enters the guides 12 of the window pane, which guides 60 not only serve to guide the screen in its movements, assisted by the slots 22 of the brackets, but also provides an insect-proof connection with the sides of the window frame, so that flies or other insects cannot 65 enter the car through the window opening.

70 It will be further observed from an inspection of Figure 1, that the bottom walls 21 of the respective brackets are disposed in the path of movement of the screen, so that when the screen is being wound about the roller 23, the channel-shaped member 26 is brought into contacting engagement with the bottom walls 21 of said brackets, which serve to limit the upward movement of the screen to its normal position. By virtue of the construction and arrangement illustrated, it is manifest that the screen is normally in an out-of-the-way position so as not to interfere with the operation of the window pane, and at the same time can be very conveniently and easily lowered for use, and held in any given position, depending of course upon how far the window pane has been lowered into an open position. The invention is also simple in construction and can be quickly and conveniently manipulated, with a possibility of the screen becoming injured or impaired reduced to a minimum.

75 80 85 90 95 While it is believed that from the foregoing description the nature and advantages of the invention will be readily apparent, I desire to have it understood that I do not limit myself to what is herein illustrated or described, and that such changes may be resorted to when desired as fall within the scope of what is claimed.

55 What I claim as new is:

1: A bracket adapted to support a screen supporting roller, including a bottom wall slotted to slidably receive the screen from said roller, and to limit the upward movement of the screen.
